UNITED STATES PATENT OFFICE.

THOMAS A. FITZSIMONS, OF SAN FRANCISCO, CALIFORNIA.

AUTOMATIC FEEDING AND WICK-RAISING LAMP.

SPECIFICATION forming part of Letters Patent No. 311,972, dated February 10, 1885.

Application filed February 15, 1884. (No model.)

To all whom it may concern:

Be it known that I, THOMAS A. FITZSIMONS, of the city and county of San Francisco, and State of California, have invented an Improvement in Self-Feeding Lamps and Clock Attachments for Feeding the Wick; and I hereby declare the following to be a full, clear, and exact description thereof.

My invention relates to a new and useful self-feeding lamp and clock attachment for feeding the wick; and it consists in an oil-reservoir from which is suspended, by an air and an oil pipe, a peculiar cup containing the burner mechanism, to the wick of which a feeding device is applied, to which motion is transmitted to feed the wick by suitable gearing connected with a clock suspended from the cup, as I shall hereinafter fully describe.

The connection of the oil-reservoir, cup, and clock, the shape of said cup, the arrangement of the wick, the construction of the feeding device, and the arrangement of gearing by which the power is transmitted from the clock, and other details, all form part of and are included in my invention, as I shall hereinafter particularly point out.

The object of my invention is to provide a lamp capable of burning a considerable time without attention by reason of the automatic feeding of the oil and wick, and therefore particularly adapted for use in churches as a sanctuary-lamp, the light of which is not intended to be extinguished. The further object is to provide in a practical manner for a combined lamp and time-piece, whereby the functions of both may be exercised and their uses enjoyed together.

Referring to the accompanying drawings, Figure 1 is a perspective view. Fig. 2 is a side elevation of the wick-feeding device and gear-wheels. Fig. 3 is a transverse section. Fig. 4 is a detail to be referred to.

A is the main receptacle or reservoir for oil, and it may be of any desired shape in general outline and cross-section, and suitably ornamented. The shape which I prefer is that shown as giving the greatest interior capacity with the least outside dimensions. This is provided with a feed-aperture, *a*, covered by an air-tight cap, *a'*. Into one side of this oil-reservoir is let a tube, B, the top of which

opens close under the cap *a'* at an elevation above whatever level of oil may be in the reservoir. Into the opposite side of the reservoir is let a tube, B', opening on the inside near its bottom. These tubes extend downwardly and open into opposite sides of the cup C, and support said cup. The tube B is for air, and the tube B' is for oil, the self-feeding operation from the upper reservoir being thus periodical, as the end of the air-tube is exposed or covered by the receding or augmenting of the oil in the cup C. The peculiar shape of this cup is a novel feature in this connection. Its bottom or lower portion, from a point about on a line with the air-tube, is very much narrowed, receding rapidly, as shown. Its upper portion is widened out, and it is provided with a gallery or shelf, *c*, and an encircling flange, *c'*. The object of this shape is to provide increased capacity on a line with and above the entrance of the air-tube, in order that a large supply of oil may be fed and contained at and above that level, the period of consumption of which will be considerable, while just below the line of the air-entrance, the capacity being materially reduced, the consumption will take place rapidly, and therefore will hasten the self-feeding operation by uncovering completely the air-entrance, and thus prevent the exposure of too great a portion of the wick. The shelf *c* promotes this result and acts as an overflow-bed, and the flange *c'* is a guard to prevent the spilling of any oil by the accidental tipping of the cup.

Over the end of the oil-tube B', I have a cut-off slide, *b*, though a valve of any other description would answer.

Standing within the cup C is a light frame, D, from which an arm, *d*, extends upwardly, and carries the slotted burner-plate E, through which the wick F projects. The wick is rolled on a reel, G, on one of the tubes B B', and thence extends downward over a gutter-way, *g*, to catch the drippings, and under a guide-roller, *g'*, to and under a guide-roller, *d'*, on arm *d*, and up through the burner-plate, as shown.

H is the globe fitted over the cup.

I is a clock of suitable description, the dial-plate of which is in full view. This clock is suspended from the cup C by means of arms

e from the cup, secured to the clock by means of screws *e*.

In Fig. 2, *J* is the shaft which carries the hour-hand of the clock. Its gear *J'* meshes 5 with a pinion, *k*, on a shaft, *K*, above, and which also carries a pinion, *k'*. This pinion meshes with a large gear, *L*, which meshes with a gear, *M*, on a shaft, *m*, mounted over the edge of cup *C*. This shaft carries a pinion, 10 *N*, which meshes with a gear, *O*, on a shaft, *o*, mounted within the cup in the top of frame *D*. This shaft carries a feed-pinion, *P*, which operates against the wick, said wick being held in contact with it by means of a roller, 15 *p*, on the other side. By this mechanism the power of the clock is transmitted up to, over, and down into the cup, and feeds the wick constantly as it is consumed. The amount of 20 this feed is a matter of calculation, and is determined by the character and number of the intervening gears.

With the clock I have used I have found it necessary to reduce the motion by the interposition of the large gear *L*; but from the 25 gear *M* it will be observed that the times of revolutions of each of the succeeding gears are equal, and therefore I am enabled to indicate on said gear the amount of feed which the wick has undergone. This I accomplish 30 by a plate, *Q*, (shown in Figs. 2 and 4,) acting as a face for said gear *M*, the plate being properly graduated.

On the shaft which carries gear *M* is a dial-finger, *q*, which moves over the graduated 35 plate *Q*, for the purpose referred to.

Any proper face-plate may be used to conceal the gears, and the whole device may be suitably ornamented.

By removing the small screw which holds 40 the frame in which the plate *Q*, gear *M*, and its shaft are contained, these parts may be removed and the lamp and clock thrown out of engagement and each perform its function separately, and, if desired, the clock itself may be 45 removed by taking out screws *e*.

I am aware that clocks and lamps have been heretofore combined in the same frame-work, each having its own function, and I do not, therefore, claim such, broadly.

Having thus described my invention, what I 50 claim as new, and desire to secure by Letters Patent, is—

1. In a lamp having an oil-reservoir from 55 which an air tube or passage and an oil tube or passage open out separately, a cup containing the burner devices, and into which the said air-tube and oil-tube open to accomplish the automatic feed of the oil thereto as the mouth of the air-tube is covered or uncovered by the oil, as described, said cup having a wide upper portion beginning about on a line with the mouth of the air-tube, and a lower portion rapidly contracting or narrowing where it joins the wide upper portion, substantially as and for the purpose herein described.

2. The main oil-reservoir *A* of a lamp, the

air-tube *B*, opening from said reservoir above the level of the oil therein, and the oil-tube *B'*, in combination with the cup *C*, which said tubes support and into which they open, as shown, said cup containing the burner device, and having a wide upper portion and a narrow lower portion of less capacity than the upper portion, said portions joining on a line with the entrance of the air-tube, substantially as and for the purpose herein described. 75

3. The main oil-reservoir *A* of a lamp and the tubes *B* *B'*, as described, in combination with the cup *C*, the frame *D*, standing therein, 80 and burner-plate *E*, supported by said frame, the reel *G*, and the wick *F* on said reel, and guided by rollers down into the cup and up through the burner-plate, substantially as herein described. 85

4. The main oil-reservoir *A* of a lamp and the tubes *B* *B'*, as described, in combination with the cup *C*, frame *D* in said cup, and burner-plate *E* on said frame, the reel *G*, supported on tube *B*, the gutter-way *g*, and the wick *F*, 90 led from said reel down into the cup and up through the burner-plate, substantially as herein described. 95

5. In a lamp having an oil-cup containing the burner device and wick, a means for feeding said wick as it is consumed, in combination with the clock *I*, suspended from the cup by arms *e*, and a mechanism for transmitting the power of the clock to operate the feeding mechanism for the wick, substantially as and for the purpose herein described. 100

6. In a lamp having an oil-cup containing the burner device and wick, the shaft *o* in said cup, and having a feed-pinion, *P*, operating against the wick to raise it, in combination with the clock *I*, suspended from the cup, and having shaft *J*, and a mechanism for transmitting the power of said shaft to the shaft *o* in the cup, substantially as and for the purpose herein described. 105

7. In a lamp, the oil-cup *C*, the frame *D*, and burner-plate *E*, the wick *F*, and the means for feeding said wick, consisting of the shaft *o*, mounted in frame *D*, the feed-pinion *P* on the shaft, and the guide or pressure roller *p*, 115 in combination with the clock *I*, suspended from the cup, and having shaft *J*, and a mechanism for transmitting the power of said shaft to the shaft *o* in the cup, substantially as and for the purpose herein described. 110

8. In a lamp, the oil-cup *C*, containing the burner device and wick, the means for feeding the wick, consisting of the shaft *o* in the cup, having pinion *P* operating against the wick, in combination with the clock *I*, having hour-hand shaft *J*, and the means for transmitting the power of the hour-hand shaft to the shaft *o* in the cup, consisting of the gear *J'*, pinions *k* *k'*, large gear *L*, gear *M*, and pinions *N* *O*, all arranged and operating substantially as herein described. 125

9. In a lamp, the oil-cup *C*, containing the burner device and wick, the shaft *o*, having feed-pinion *P* and pinion *O*, the shaft *m*, hav-

ing pinion N and gear M, the graduated face-plate Q, and dial-finger *q* on shaft *m*, in combination with the clock I, suspended from the cup, and a mechanism for transmitting the power of the clock to the gear M, whereby the wick is continually fed and its feed indicated, substantially as herein described.

10. The self-feeding lamp consisting of the main oil-reservoir A, air-tube B, oil-tube B', and cup C, which said tubes support and into which they open, said cup containing the burner device and wick and a means for feeding

the wick, in combination with the clock I, suspended from the cup, and a mechanism for transmitting the power of the clock to the means for feeding the wick, whereby said means may be continuously operated, substantially as herein described.

In witness whereof I have hereunto set my hand.
